CLAIM

The ornamental design for an undercabinet lighting fixture incorporating positionable mounting, as shown and described.

DESCRIPTION

FIG. 1 is a bottom perspective view of an undercabinet lighting fixture incorporating positionable mounting illustrating my new design;

FIG. 2 is a left side elevation view thereof, the right side elevation view being identical;

FIG. 3 is a front elevation view thereof;

FIG. 4 is a rear elevation view thereof;

FIG. 5 is a top plan view thereof; and,

FIG. 6 is a bottom plan view thereof.
